Primary Examiner — Cynthia M. Chin(74) *Attorney, Agent, or Firm* — Daryl R. Wright; Greg Carr(57) **CLAIM**

We claim the ornamental design for a model vehicle track assembly, as shown and described.

DESCRIPTION

FIG. 1 is an upper, left, front perspective view of a model vehicle track assembly, showing our new design;

FIG. 2 is front elevation view thereof;

FIG. 3 is a rear elevation view thereof;

FIG. 4 is a left side elevation view thereof;

FIG. 5 is a right side elevation view thereof;

FIG. 6 is an upper plan view thereof;

FIG. 7 is a lower plan view thereof; and,

FIG. 8 is an upper, left, front perspective environmental use view.

In the drawings, the broken lines are for the purpose of illustrating portions of the article that form no part of the claimed design.

In the drawings, the representative model vehicle track assembly depicted is a left model vehicle tract assembly. The right rear model vehicle track assembly is a mirror image of the left rear model vehicle track assembly.
